DESIGN FOR A COMBINED LUGGAGE RACK AND LIGHTING FIXTURE

Albert L. Arenberg, Highland Park, Ill., assignor
to Patent License Corporation, Chicago, Ill., a
corporation of Illinois

Application November 2, 1945, Serial No. 123,421

Term of patent 14 years

(Cl. D48—4)

To all whom it may concern:

Be it known that I, Albert L. Arenberg, a citizen of the United States, residing at Highland Park, in the county of Lake and State of Illinois, have invented a new, original, and ornamental Design for a Combined Luggage Rack and Lighting Fixture, of which the following is a specification, reference being had to the accompanying drawing, forming a part thereof.

In the drawing:

Fig. 1 is a fragmentary bottom plan view of the combined luggage rack and lighting fixture, showing my new design;

Fig. 2 is an enlarged transverse view in section, taken on a line corresponding to line 2—2 of Fig. 1; and

Fig. 3 is a fragmentary view in front elevation, looking to the left in Fig. 2.

The dominant features of my design reside in the portions shown in full lines.

I claim:

The ornamental design for a combined luggage rack and lighting fixture, substantially as shown and described.

ALBERT L. ARENBERG.
